UNITED STATES PATENT OFFICE.

PETER ALLINIO, OF SAN PABLO, CALIFORNIA.

CEILING CONSTRUCTION.

No. 914,102.

Specification of Letters Patent. Patented March 2, 1909.

Application filed August 15, 1908. Serial No. 448,696.

To all whom it may concern:

Be it known that I, PETER ALLINIO, a subject of the King of Italy, and a resident of San Pablo, in the county of Contra Costa and State of California, have invented a new and Improved Ceiling Construction, of which the following is a full, clear, and exact description.

This invention relates to certain improvements in ceiling construction and more particularly to the means employed for supporting metallic lath below concrete floors.

The object of my invention is to eliminate the furring-strips and support the lath directly from the concrete constituting the floor and at a distance therefrom. The construction is thus rendered fire-proof, the total thickness is reduced and the plaster may be applied immediately after the wooden forms are removed.

Reference is to be had to the accompanying drawings forming a part of this specification, in which similar characters of reference indicate corresponding parts in all the views.

Figure 1 is a plan view of a section of metallic lath which I may employ; Fig. 2 is a side view of one of the binding or tying strips employed; Fig. 3 is a vertical section through a portion of a wooden frame, showing the lathing in position and ready to receive the concrete; Fig. 4 is a vertical section through the concrete floor, ready to receive the plaster on the lathing therebeneath, and Fig. 5 is a vertical section through a portion of the complete structure with the plaster in place.

In carrying out my invention, I employ any suitable form of metallic lath, as, for instance, sheets 10 of expanded metal of the type illustrated in Fig. 1. To this expanded metal lathing I secure a plurality of ties, supports or binding strips 11, substantially as illustrated in Fig. 2. Each of these strips is provided with a plurality of teeth 12 along the lower edge thereof, and the main body 45 portion of each strip is provided with a plurality of apertures or perforations 13. The tying, binding or supporting strips 11 are placed either transversely or longitudinally of the lathing with the teeth 12 extending 50 through apertures in the latter. Adjacent teeth are then bent in opposite directions to securely fasten the strips to the sheet. In employing this lathing the wooden forms which receive the concrete are supported at 55 a slightly lower level than is customary.

In Fig. 3 I have illustrated one I-beam 14,

serving to support the concrete of the floor, and beneath this I-beam I mount a temporary wooden form 15, the upper surface of the bottom of which comes at a slight distance below the lower surface of the I-beam. The lathing is then placed directly upon the bottom of the wooden form and the strips 11 extend upwardly therefrom, but terminate at a lower level than the upper surface of the I-beam. The wooden form is then partially filled with a layer of sand 16, so as to completely cover the lathing and the lower portion of each of the binding strips 11. The mold is then ready to receive the concrete 17, which is carefully poured in so as not to displace the sand. Concrete of sufficient stiffness or hardness is employed, so that it does not permeate the sand to any material extent. As soon as the concrete is hardened the wooden form may be removed and the layer of sand will pass down through the apertures in the expanded metal lathing, so as to leave said lathing spaced from the concrete 17 but rigidly supported in respect thereto by means of the tying strips 11. The laterally-bent teeth of the said strips support the lathing and the apertures in said strips permit the concrete to pass therethrough, so as to firmly hold the strips within the concrete. As soon as the wooden form and the sand have been removed, the plaster 18 may be applied to the metal lathing at once, without the insertion of any furring-strips or other auxiliary construction. It is not necessary to wait for the concrete to dry, other than sufficient to permit of the removal of the wooden form; thus considerable time may be saved in the construction of a large building.

The absence of the furring-strips renders the construction thoroughly fire-proof, and in case the lath is spaced from the concrete to the extent indicated in Figs. 4 and 5 an air chamber is left in between the plaster and the concrete, which forms an insulation against the passage of heat, as well as noises. Preferably, the strips 11 are provided with a series of openings 13^a adjacent their lower edges, whereby the air may circulate from one air chamber to the next. If desired, a smaller quantity of sand may be employed, so that the lathing will come closely adjacent the concrete and plaster and pass through the lathing directly into contact with the concrete.

I have referred to the use of sand as a

material for preventing the concrete from coming into contact with the lath but it is evident that any other suitable material might be employed which could be removed in whole or in part through the openings in the lathing.

Having thus described my invention, I claim as new and desire to secure by Letters Patent:

- 10 In combination, a concrete flooring, binding strips having perforations therethrough and terminating in teeth or tongues at their lower edges, said binding strips having their upper edges embedded within said concrete
- 15 and held therein by the engagement of the concrete with certain of said perforations, reticulated metal lathing secured to the

lower portions of said binding strips by means of said tongues or teeth, and a ceiling of plastic material supported from said lathing and spaced from said flooring, certain of the perforations in said binding strips being disposed between said flooring and said lathing and permitting a circulation of air through said binding strips and within 25 the spaces intervening between said ceiling and flooring.

In witness whereof I have signed my name to this specification in the presence of two subscribing witnesses.

PETER ALLINIO.
